UNITED STATES PATENT OFFICE.

CALVIN C. FOUTS AND ARTHUR A. AMBLER, OF MIDDLETOWN, OHIO, ASSIGNEES TO
THE C. C. FOUTS COMPANY, OF MIDDLETOWN, OHIO, A CORPORATION OF OHIO.

FLUME.

1,176,283.

Specification of Letters Patent.

Patented Mar. 21, 1916.

Application filed January 15, 1915. Serial No. 2,331.

To all whom it may concern:

Be it known that we, CALVIN C. FOUTS and ARTHUR A. AMBLER, citizens of the United States, residing at Middletown, in the county of Butler and State of Ohio, have invented certain new and useful Improvements in Flumes, of which the following is a specification, reference being had therein to the accompanying drawing.

10 This invention relates to flumes and to conduits and receptacles of similar construction.

15 The object of the invention is to provide a structure of this character which may be built up of sections and which will form a smooth interior surface offering little or no resistance to the flow of the water; to provide a device of this kind which will be very simple in its construction comprising but a 20 few parts and having these parts of such a character that the structure as a whole may be manufactured at a low cost.

25 A further object of the invention is to provide a sectional structure of this kind in which the sections may be connected one to the other without bending or changing the shape of the body portion thereof, thus avoiding injury to the galvanized surface, where sheet metal is used.

30 A further object of the invention is to provide an improved means for supporting a sheet metal structure of this kind.

35 In the accompanying drawings, Figure 1 is a side elevation, partly broken away, of a portion of a flume constructed in accordance with our invention; Fig. 2 is a transverse sectional view taken on the line *a a* of Fig. 1; Fig. 3 is an enlarged section of the upper portion of one side of the structure 40 shown in Fig. 2; Fig. 4 is a sectional view, taken on the line *b b* of Fig. 1; Fig. 5 is a perspective detail view of the pressure plate; and Fig. 6 is a horizontal section taken on the line *c c* of Fig. 3.

45 In these drawings we have illustrated one embodiment of our invention and have shown the same as applied to a flume comprising a series of sections having their adjacent ends overlapping. In the present instance all of the sections are formed of sheet metal, preferably galvanized iron, although it will be obvious that a part or all of the sections may be formed of other material. Each of the sections of the flume, which are

shown at 1, is trough-shaped and, in the present instance, is substantially semicircular in cross section. As here shown each trough-like section constitutes a part of the conducting surface of the flume, but this is not essential, as a part of the sections may be connecting devices between other sections. The flume is set at a slight angle to cause the fluid to flow readily down the same and the lower end of each upper section thereof overlaps and lies within the upper end of the next lower section thereof. To form a tight joint between the two sections and to accomplish this without bending or changing the shape of the ends of the sections and without the use of clamping rods, bars or the like, we have provided means to exert pressure on one of the sections in such a manner as to cause it to press firmly against the overlapping portion of the other section, thereby forming a joint which will be tight and which will offer no obstruction to the flow of the water except a slight fall over the end of the inner section and this fall being only for the thickness of the sheet metal, or other material, is so small that it has no appreciable effect upon the flow of the water. While this pressure may be applied in various ways we have, in the present drawings, illustrated one form of device which is very efficient. As here shown the connection is made by providing pressure devices at the opposite lateral edges of the overlapping portions of the sections, which pressure devices are connected with the outer section and are arranged to act upon the inner section to force the same toward and into firm engagement with the outer section throughout the width of the sections between the two pressure devices, the pressure on the edges of the inner section being directed substantially in line with the respective upper portions of said sections, so that there is no tendency to spring the sheets apart or distort the same. To accomplish this we have provided the sections in their upper lateral portions with sockets adapted to receive a bolt 2 which is so connected with the outer section as to be held normally against vertical movement relatively thereto but which is disconnected from the inner section so that the latter is free to move lengthwise thereof. In the present instance the adjacent upper portions of the two sec-

tions are provided with opposed grooves 3 and 4 which, when the two sections are in their assembled positions form a socket for the bolt. The grooved portion 4 of the outer section is of less length than the grooved portion 3 of the inner section and the outer section is provided with an opening at the lower end of the groove 4, thereby permitting the lower edge of the grooved portion of the section to form a stop against which the head of the bolt 2 engages and which serves to hold the bolt against vertical movement relatively to the outer section. To enable the bolt to be placed in position without interfering with the vertical movement of the inner section we have cut away one side of the head of the bolt, but obviously other means could be provided which would permit of the necessary movement of the inner section relatively to the bolt, which movement is very slight. The grooves and aperture entering into the construction of the socket may be formed in any suitable manner, as by pressing them into the sheet metal.

Mounted upon the upper end of the bolt 2 and overlapping the upper edges of the two sections of the structure is a pressure plate or washer 5 which engages the upper edge of the inner section, which, because of the overlapping arrangement of the sections, projects a short distance above the adjacent portion of the outer section. A nut 6 is screw-threaded onto the outer end of the bolt and serves to force the clamping plate downward and thus press the inner section firmly against the overlapping portion of the outer section. Preferably, the pressure plate is U-shaped in cross section, as shown in Figs. 3 and 5, this construction serving both to hold the plate in its proper position relative to the edges of the two sections and also serving to prevent the lateral displacement of the upper portion of the sections themselves. In the present construction we have shown one of these adjustable pressure devices at each lateral edge of the flume but it will be understood that an adjustable pressure device may be applied to one edge only of the flume and a fixed pressure device or stop applied to the other edge and that the adjustment of the adjustable device will exert the desired pressure on the overlapping portion of the inner section and that this pressure will be distributed throughout the width of the section. The pressure device here shown constitutes such a fixed stop when it is applied to one side of the flume and all the pressure on the inner section is secured by the adjustment of the device on the other side of the flume. However, the present adjustable pressure device is so inexpensive in its construction that it is preferable to use one on each side of the flume, as this simplifies the assembling and

connection of the sections. It will be noted that to assemble the flume or other structure it is only necessary to place the sections in their overlapping positions, the grooves 3 and 4 having been previously formed there-in. As soon as these grooves have been brought into registration to form the socket the bolt 2 may be inserted in the socket, the outer section being bent inward to provide a recess, as shown at 7, to facilitate the insertion of the bolt. Either before or after the bolt is inserted the pressure plate 5 is placed in position and the nut is then applied to the end of the bolt and one or both nuts adjusted until the inner section has been caused to press against the outer section with sufficient pressure to provide a tight joint. Ordinarily, and particularly where the structure is used for conducting water, it is unnecessary to provide any sealing agent between the overlapping portions of the two sections, as the sediment in the water will quickly fill up any small spaces or openings which may exist and make the joint a perfectly water tight one. If desired, a layer of oil or white lead may be applied to the overlapping portions of the two sections. When the structure is used to contain or conduct certain fluids, however, it is desirable that a sealing agent should be employed and we have therefore shown the outer section, in Fig. 1, as provided with a shallow groove 8, which is not deep enough nor the corners thereof sharp enough to injure the galvanized surface of the metal, and in this groove we have shown a cement 10, which may be of any suitable character.

Flumes are commonly supported on wooden trestles or frames and for this purpose we have provided the structure on either side with a series of brackets 11 which are rigidly secured to the upper lateral portions of the several sections and are adapted to be secured to the supporting frame. To provide a strong rigid connection between the bracket and the flume the section to which the bracket is to be attached is provided with a boss 12, the lower portion of which forms a shoulder extending outwardly from the upper portion of the section. Where the device is formed of sheet metal, as in the present instance, this boss also forms a recess to receive the head 13 of a fastening bolt 14 which extends through bolt holes in the boss and a downwardly extending portion 15 of the bracket. The head 13 is square and the bottom surface of the recess is flat, whereby when said recess receives the head the latter is prevented from rotating and is securely connected to the bracket 11 by means of its nut. This downwardly extending portion of the bracket is also recessed, as shown at 16, to receive the boss 12 and to provide a shoulder which will co-operate with the shoulder of the boss 13.

When the bolt is in position and its nut has been tightened down the bracket is rigidly secured to the wall of the section and the weight is carried by the interlocking bosses 5 of the bracket and the flume section, thus relieving the bolts of the strain and avoiding any tendency on the part of the bolts to shear. While we have shown the boss as a means of attaching a sheet metal bracket to 10 the flume it will be apparent that the shoulder which is formed by the boss may coöperate with a bracket of any kind or that it may coöperate directly with the wooden frame, in which latter case a nail or screw 15 will be substituted for the bolt.

We are aware that sectional flumes have been provided in which the ends of adjacent sections overlap and are provided with 20 grooves to receive a clamping rod, but this construction has been found to be objectionable because of the necessity of using a 25 clamping rod on the inside of the flume which makes it impossible to provide a smooth continuous surface and which further requires a distorting of the sections 30 with the consequent liability of injuring the galvanized surface of the metal.

While we have shown and described one embodiment of our invention it will be understood that this has been chosen for the purposes of illustration only and that we do not desire to be limited to the details of construction shown and described, for obvious 35 modifications will occur to a person skilled in the art.

Having thus fully described our invention, what we claim as new and desire to secure by Letters Patent, is:—

1. In a structure of the character described, the combination, with trough-like sections having their adjacent ends overlapped, of a connecting member arranged 40 between the upper edges of said overlapping portions of said sections and projecting above said edges, said connecting member being held against longitudinal movement in one direction relatively to said outer section, and a pressure plate adjustably mounted on said connecting member and arranged 45 to engage the upper edge of the inner section and exert pressure thereon in substantial alinement therewith.

2. In a structure of the character described, the combination, with trough-like 55 sections having their adjacent ends overlapped, of a connecting member arranged between the upper edges of said overlapping portions of said sections and projecting above said edges, said connecting member 60 being held against longitudinal movement in one direction relatively to said outer section, a pressure plate mounted for longitudinal movement on said connecting member and arranged to engage the upper edge of 65 the inner section, and means carried by said

connecting member to adjust said plate relatively to said inner section and to hold the same in its adjusted position.

3. In a structure of the character described, the combination, with trough-like sections having their adjacent ends overlapped, of a bolt arranged between the upper edges of the overlapping portions of 70 said sections and projecting above said sections, said bolt being held against longitudinal movement in an upward direction relatively to said outer section, a pressure plate loosely mounted on said connecting member and arranged to engage the upper edge of the inner section, and a nut mounted 75 on said bolt to force said pressure plate against the upper edge of said inner section.

4. In a structure of the character described, the combination, with trough-like sections having their adjacent edges overlapped, of a connecting member arranged 80 between the upper edges of said overlapping portions of said sections and projecting above said edges, said connecting member and said outer section having coöoperating 85 parts to hold said connecting member against upward movement relatively to said outer section, and a pressure plate adjustably mounted on said connecting member and arranged to engage the upper edge of 90 said inner section and exert pressure thereon in substantial alinement therewith.

5. In a structure of the character described, the combination, with trough-like sections having their adjacent ends overlapped, a connecting member arranged 100 between the upper edges of said overlapping portions of said sections and projecting above said edges, the outer section having an opening adjacent to said connecting member and said connecting member having a lateral projection entering said opening and serving to hold said connecting member against upward movement, and a pressure plate adjustably mounted on said connecting member 105 and having depending portions to embrace the upper portions of said sections.

6. In a structure of the character described, the combination, with trough-like sections having their adjacent ends overlapped, of a bolt secured to the upper portion 110 of the outer section and extending above the edge thereof in substantial alinement therewith, a pressure plate mounted on said bolt and capable of movement longitudinally thereof, and means carried by said bolt to force said pressure plate against the upper edge of the inner section.

7. In a structure of the character described, the combination, with trough-like 115 sections having their adjacent ends overlapped, of a bolt connected with the upper portion of the outer section and projecting above the upper edge thereof in substantial 120 alinement with the upper portion thereof, a 125

130

pressure plate substantially U-shaped, in cross section and arranged to embrace the upper portions of the two sections and to rest upon the upper edge of the inner section, and a nut on said bolt to press said plate into engagement with the upper edge of said inner section.

8. In a structure of the character described, the combination, with trough-like sections having their adjacent ends overlapped, the overlapped portions of said sections having opposed grooves arranged at substantially right angles to the edges of said sections and the outer section having a part forming a stop, of a bolt mounted in said grooves between said sections with its head in engagement with said stop, a pressure plate mounted on said bolt and extending across the upper edge of the inner section, and a nut mounted on said bolt above the pressure plate.

9. In a structure of the character described, the combination, with trough-like sections having their adjacent ends overlapped, the overlapping portions of said sections having opposed grooves arranged at substantially right angles to the lateral edges thereof and adapted to form a socket between said sections, of a bolt mounted in said socket, the outer section having an aperture near the lower end of its groove to permit the insertion of said bolt and to form a shoulder to engage the head of said bolt and limit the upward movement thereof relatively to said outer section, the inner section being free to move relatively to said bolt, a pressure plate mounted on said bolt in engagement with the upper edge of the inner section, and a nut mounted on said bolt above said pressure plate.

10. In a structure of the character described, the combination, with trough-like sections having their adjacent ends overlapped, the overlapping portions of said sections having opposed grooves arranged at substantially right angles to the lateral edges thereof and adapted to form a socket, of a bolt mounted in said socket, the outer section having an aperture near the lower end of its groove to permit the insertion of

said bolt and to form a shoulder to engage the head of said bolt and limit the upward movement thereof relatively to said outer section, the inner section being free to move relatively to said bolt, a pressure plate substantially U-shaped in cross section mounted on said bolt and having its side portions embracing the upper edges of the two sections, and a nut mounted on said bolt to force said pressure plate against the upper edge of the inner section.

11. A sheet metal flume or the like having a boss struck out therefrom near the upper edge thereof, said boss constituting a recess at its rear, a supporting bracket having a depending portion provided with a recess to receive said boss, said boss and the wall of said recess forming coöoperating shoulders, said boss and said recess having apertures, and a bolt having an angular head extending through said apertures, said head extending into the first-mentioned recess, whereby said bracket and flume are fastened together and the bolt is prevented from rotating in said apertures. 75

12. In a structure of the character described, the combination, with trough-like sections having their adjacent edges overlapped, and devices connected with the overlapping portions of the respective sections 80 to keep the said sections in engagement with each other, of supporting devices rigidly secured to the respective sections between the ends thereof, said supporting devices comprising bosses struck outward from the sections of a flume near the upper edges thereof, supporting brackets having depending portions provided with recesses to receive said bosses, said bosses and the walls of said recesses forming coöoperating shoulders, said 85 bosses and said brackets having apertures, and bolts extending through said apertures to fasten said brackets to said flume. 90

In testimony whereof, we affix our signatures in presence of two witnesses.
